IMPLEMENT FOR CUTTING CABLE SHEATHS

John Boulware Doolittle, Kansas City, Mo.

Application January 6, 1937, Serial No. 119,339

1 Claim. (Cl. 30—91)

This invention relates to implements which are more particularly adapted to be used in connection with lead sheaths of cables. More specifically these implements involve knife members by which openings, such as slits, may be made in the sheaths of cables.

It has been found, in the use of aerial transmission cables, that sheath breaks, ring cuts, fatigue cracks and other minor injuries occur in their lead sheaths and permit the entrance of moisture. This causes short-circuiting, grounding or other damage to the insulated conductors contained in the cable, and it is necessary, in order to clear this condition, that the cable sheath be opened at the point of injury so that access may be obtained to withdraw the damaged portions of the conductors for repair.

Accordingly, it is an object of this invention to provide a simple and comparatively inexpensive implement by which an incision may be made in a cable sheath for the purpose outlined above. This and further objects will be apparent from the following description, when considered in connection with the accompanying drawing, in which one embodiment of the invention is illustrated.

Referring to the drawing, Figure 1 is an elevation illustrating the operating or sheath engaging face of the improved implement; Fig. 2 is a view showing the implement rotated at an angle of 90 degrees from the position shown in Fig. 1; Fig. 3 is a top view of the implement; Fig. 4 is a view similar to Fig. 3 showing a knife guard in position thereon; and Fig. 5 is a perspective view of the knife guard.

This improved implement is preferably made of a light durable metal such as aluminum, and the handle portion thereof is shown at 5 in the drawing. The handle portion is of such size and contour that it may be readily grasped and manipulated. Shoulders 6 and 7 are formed at the ends of the handle portion and serve to provide stops which tend to prevent the hands slipping while operating the device. These shoulders may be of any desired formation; for instance, they may be substantially rectangular, as shown in Figs. 1 and 2. One of the faces of each of these shoulders has sheath-engaging grooves formed therein, as illustrated at 8 and 9. These grooves may be of substantially V-shape and a portion of one side of the groove 8 is cut away. In the operation of the improved device the side of the groove having the cut-away portion may be held next to the user so that the cutting action of the knife blade, to be presently

described, may be observed through said portion as the blade is drawn along the cable sheath. This cut-away portion also permits the escape of lead shavings during the cutting operations of the sheath.

A channel is provided on the end of the shoulder 6 and the knife 11 may be adjusted by moving it back and forth therein until it is in the desired position. The knife has two blades, 12 and 13, which may be of the formation illustrated. The blade 12 is of smaller dimension than the blade 13 and is initially used to penetrate the lead sheath while the blade 13 is subsequently used to enlarge the cut made by the blade 12, as will be presently described. The points of these blades are sharpened so that when used to cut a cable sheath they rout the lead in a manner similar to the action of a wood plane. The knife 11 has a longitudinal slot 14, provided centrally therethrough, and a threaded stud 15, carried on the end of the shoulder 6, extends through the slot. The stud 15 is shown as having a wing nut 16 on its threaded extremity which serves, when screwed down, to provide a clamping action of the knife 11 to maintain it in any desired position to which it may be moved in the channel.

A guard 17, as more clearly shown in Fig. 5, is provided for the knife 11. This guard is applied at times when the implement is not in use to prevent injury by cutting. The knife guard has an angular slot 18 which permits it to be slipped in position about the stud 15 and on top of the knife when the nut 16 is loosened. The tightening of said nut clamps the guard and knife in position. The guard is provided with downwardly extending flanges 19 and 20. When the guard is in position the flange 19 abuts and extends along one edge of the blade 13 and slightly beyond its point. The other edge of the blade 13 is protected by an overhand portion of the guard, as more clearly shown in Fig. 4. The flange 20 forms a shield over the blade 12.

This implement is ordinarily employed to make slits in cable sheaths in a longitudinal direction. The small blade 12 is used initially to penetrate the sheath and is adjusted to cut the sheath to a desired depth. The grooved ends 8 and 9 of the shoulder portions are laid against and pulled along the cable sheath to make an incision of the length desired. The implement is turned over for the next operation and a larger blade 13 is drawn along in the incision just described to bevel-cut the sheath. It is preferred to again

reverse the implement and use the smaller blade 12 to make the final cut to obtain access to the insulated conductors in the cable. When cut as desired the slit portion of the cable sheath may be pulled apart by pliers or other suitable means 5 to provide sufficient space through which the damaged portions of the insulated conductors may be withdrawn for repair.

While the arrangements of this invention have 10 been illustrated as embodied in a certain specific form which has been deemed desirable, it will be understood that they are capable of many and widely varied forms without departing from the spirit of the invention as defined in the ap- 15 pended claim.

What is claimed is:

An implement for slitting lead sheaths of cables including a handle portion, shoulder members at the ends of and extending transversely from the axis of the handle to space the handle 5 from the cable sheath, said shoulder members forming stops tending to prevent the slipping of the hand in the operation of the implement, said shoulder members also having aligned grooves therein for slidably engaging the cable sheath 10 in the movement of the implement along its surface, and a knife member adjustably mounted on the end of one of the shoulder members for slit-ting the cable sheath in a longitudinal direction.
